TWISTING OR STRAIGHTENING
MECHANISM

George E. Nighthart and Edward M. Wheeler, New
Kensington, Pa., assignors to Aluminum Com-
pany of America, Pittsburgh, Pa., a corpora-
tion of Pennsylvania

Application May 16, 1938, Serial No. 208,110

3 Claims. (Cl. 153—78)

This invention relates to the straightening of bars, shapes, and the like, which, after being given their cross-sectional configuration by rolling, extrusion, and like processes, are found to be warped, twisted, or skewed. More particularly, 5 the invention relates to straightening such products by applying to a pre-formed shape a torsional force, sufficient to stress it beyond its elastic limit, at any desired point or points along 10 the length of the shape.

It is an object of this invention to provide an improved device for use in connection with material or shape-stretching machines to the end that every type of irregularity in such shapes may be satisfactorily and efficiently removed. It is another object of the invention to provide a means 15 for removing twists which extend only through a portion of the length of a pre-formed shape, or twists which are not uniform. The device of the 20 invention, which is hereinafter termed a "twisting head," is designed to be used in conjunction with material stretchers equipped either with a fixed stretching head or with a rotating stretching head such as, for example, the type of mechanism shown in the copending application, Serial No. 121,483, filed January 21, 1937. The device of the invention is adapted to be positioned 25 on the bed of such a stretcher mechanism, and may be moved to any desired position between 30 the head and tail stocks.

In the production of shapes or bars, or the like, particularly extruded shapes, various types of deformity appear in the members as produced. Of the common deformities, the most difficult to 35 remove are twists or skewes which are non-uniform throughout the length of the shape, and twists or skewes which are oppositely disposed with respect to the longitudinal axis of the shape. The invention is designed to efficiently remove 40 such deformities with a minimum of handling and the least number of operations.

In order to describe and explain the invention in terms of an actual installation, reference is 45 hereinafter made to the accompanying drawings, forming a part of this specification, in which:

Figure 1 represents a side elevation of a twisting head, with portions of the belt and gear housings broken away to more clearly show the mode 50 of construction;

Figure 2 represents an end view of the same device with a portion of the gear housing broken away;

Figure 3 is a sectional elevation taken along 55 the line III—III of Figure 4; and

Figure 4 is a sectional elevation taken along the line IV—IV of Figure 3.

The twisting head of this invention is preferably mounted upon a bed 1 of a stretcher mechanism along which it may be moved or translated through the medium of wheels 2 which are actuated by a suitable reversible motor 3, directly connected to said wheels by means of a train of gears 4. When in proper position longitudinally of a member or shape to be straightened, the twisting or straightening head of the invention is clamped to the bed 1 by means of clamp members 5 which are pivotally hinged at 6 to the frame 12 of the twisting head. In Figure 4 the left-hand clamp 5 is illustrated in its open position for traveling along the bed, and the right-hand clamp is shown in engagement with the bed 1 to secure the twisting head in position with respect to the bed. A shouldered screw 7 is suitably mounted for rotation, as by 20 means of the hand wheel 8, in a journal member 9 which is pivoted upon the clamp 5 on a pin 10. The threads of the screw 7 cooperate with complementary threads in a bar member 11 which is oscillatably mounted in the frame 12, whereby 25 rotation of the screw 7 brings the clamp 5 into clamping relationship with the underside of base 1. A set screw 13 is provided to adjustably fix the clearance between the base 1 and the clamp 5 for longitudinal travel. 30

In Figures 3 and 4, the bar or shape to be straightened is gripped between suitably shaped jaws 14, which are designed to grip the shape without distorting the same. In Figure 4, a channel is shown in dotted lines in the central 35 position in which the jaws will engage it. Each jaw is mounted on a suitable screw 15, the threads of which cooperate with internal threads in a sleeve 16. The sleeves 16 are provided with external threads which cooperate with complementary threads in fixed nuts 17. The sleeves 16 are rotated by gears 18 mounted thereon and cooperating with gears 19 keyed to a suitable shaft 20. The shaft 20 is driven by a worm and worm wheel mechanism 21, a hand wheel 22 being provided for imparting rotation to the shaft 20. The upper and lower jaws are simultaneously actuated by the common shaft 20, whereby 40 rotation of the hand wheel 22 brings the jaws 14 into engagement with the pre-formed shape to 45 grip the same, so that it is held at the center of rotation of the twisting head proper.

The entire jaw operating mechanism above described is rigidly mounted on a rotatable slotted wheel 23, which is constructed in the form of a 50

gear from which a section has been omitted so that pre-formed material to be straightened may be inserted conveniently in the jaws 14 in a plane perpendicular to the plane of rotation of the slotted wheel 23. This omitted section will be hereinafter termed the "slot." The perimeter of the slotted wheel 23 is provided with a raised center portion 24 constructed in the form of suitable gear teeth, track surfaces 25 being provided on either side of the raised center portion 24. The slotted wheel 23 is supported by a suitable number of rollers 26 which are rotatably mounted upon shafts 27 mounted in the frame 12, the rollers 26 defining the center or path of rotation of the slotted wheel 23.

The gear teeth 24 are preferably constructed as herring bone teeth, and engage complementary herring bone pinions 28 and 29, the latter being keyed to oppositely disposed shafts carrying spur gears 30. The pinions 28 and 29 are so positioned that the distance between their points of engagement with the gear teeth 24 of the slotted wheel is greater than the width of the slot in the wheel 23. Since the shafts supporting the two pinions 28 and 29 are rotated through the medium of a common gear 31 in engagement with gears 30, it will be seen that at least one of the pinions 28 and 29 will always be in engagement with the toothed surface 24 of the slotted wheel 23 for all positions of this wheel. Hence the slotted wheel may be driven in either direction, regardless of the position of its slot. The drive pinion 31, which imparts rotation to the gears 30 and pinions 28 and 29, is mounted upon a shaft 33, which 35 shaft has a suitable belt pulley 32 keyed thereto. Pulley 32 is belt-connected to a similar pulley secured to the shaft of a suitable reversible motor 34, which provides means for rotating the slotted wheel 23. In order that the slotted wheel may 40 be definitely and selectively positioned with regard to the frame 12, a brake 35, actuated by a solenoid 36, is mounted on the shaft of the motor 34. The motor is also mounted on a platform 37 which is hingedly connected at 38 to the main 45 frame 12 of the twisting head, a pivoted rod 39 passing through the platform 37 and adjustably secured to the platform 37, as by suitable nuts 40 threaded on the rod 39, providing adjustable means for regulating the tension of the belt from 50 the motor 34 to pulley 32.

In order to minimize any danger of accidental damage to a stretching machine employing one or more of the twisting mechanisms of the invention, bumper rods 41 are provided in the lower portion of frame 12. Springs 42 are positioned upon turned down portions of the rods 41 and serve to cushion any shock received through possible collision between a twisting head and other mechanisms, or head or tail stocks.

In operation, one or more of the twisting heads, hereinabove described, is mounted on the bed of a stretcher mechanism between its head and tail stocks. The shape to be straightened is secured in the head and tail stocks, and the jaws 14 of the straightening or twisting head of the invention are manipulated, through the medium of the hand wheel 22, into position to clamp or grip the shape to be straightened. Torsional stress is thereafter imparted to the clamped shape or section by means of rotating the slotted wheel 23 in the proper direction to remove the twist existing in the shape. The introduction of this torsional stress may occur either prior to or during the longitudinal stretching operation, both

modes of imparting torsional stress having been found exceedingly satisfactory in practice.

The twisting head of the invention, which may be referred to as an intermediate twisting head to distinguish the same from the tail or head stocks of a stretching mechanism, either or both of which may be designed for rotation, is adapted to be used in conjunction with stretchers having a fixed head or having a rotating head such as, for example, that described in the copending application hereinbefore mentioned. If the heads or tail and head stocks of the stretcher mechanism, to which the intermediate twisting head of this invention has been adapted, are both incapable of rotation, the intermediate head may serve the additional useful purpose of rotating the end of a pre-formed shape after its opposite end has been clamped in the tail stock of the stretcher mechanism, whereby the shape may be twisted into position to be gripped by the head stock of the stretcher mechanism.

While the description of this invention has been limited to a specific embodiment of the invention, it will be apparent that many modifications thereof will present themselves to those skilled in this art, and it is the intent that such modifications are to be considered as having been contemplated within the scope and spirit of the appended claims.

What is claimed is:

1. In a twisting mechanism for straightening bars and shapes, a frame, a plurality of rollers mounted in said frame, means adapted for rotation within a path defined by said rollers, clamping means mounted in said rotatable means accessible to the insertion of a work-piece in a plane perpendicular to the plane of rotation, and means adapted to drive said rotatable means at points spaced apart a distance greater than the distance provided for the insertion of the work-piece, said clamping means being actuated from a common driving means, whereby the work-piece is centered at the center of rotation of said rotatable means.

2. In combination with a stretching machine, a twisting mechanism for straightening bars and shapes, a frame, a plurality of rollers mounted in said frame, means adapted for rotation within a path defined by said rollers, clamping means mounted in said rotatable means accessible to the insertion of a work-piece in a plane perpendicular to the plane of rotation, and means adapted to drive said rotatable means at points spaced apart a distance greater than the distance provided for the insertion of the work-piece, said clamping means being actuated from a common driving means, whereby the work-piece is centered at the center of rotation of said rotatable means.

3. In a twisting mechanism for straightening bars and shapes, a frame, a plurality of rollers mounted in said frame, means adapted for rotation within a path defined by said rollers, clamping means mounted in said rotatable means accessible to lateral insertion of a work-piece in a plane perpendicular to the plane of rotation, and means adapted to drive said rotatable means, said clamping means being actuated from a common independent driving means, whereby the work-piece is centered at the center of rotation of the rotatable means.

GEORGE E. NIGHTHART.
